CLAIM

The ornamental design for a Y-adapter, as shown and described.

DESCRIPTION

FIG. 1 is a perspective view of a Y-adapter, showing my new design;

FIG. 2 is a top view of the Y-adapter shown in FIG. 1; a bottom view of the Y-adapter shown in FIG. 2 is a mirror image of the top view shown; and,

FIG. 3 is a side view of the Y-adapter shown in FIG. 1; the opposite side of the view shown in FIG. 3 is a mirror image of the side view shown.

The broken line showing of the environment is for illustrative purposes only and forms no part of the claimed design.
